UNITED STATES PATENT OFFICE.

WILLIAM P. HANNAFORD, OF NEWTON, MASSACHUSETTS, ASSIGNOR TO THE CLARK MANUFACTURING COMPANY, OF BOSTON, MASSACHUSETTS, A CORPORATION OF NEW JERSEY.

GARMENT-CLASP.

964,968.

Specification of Letters Patent. Patented July 19, 1910.

Application filed February 27, 1908. Serial No. 418,015.

To all whom it may concern:

Be it known that I, WILLIAM P. HANNAFORD, a citizen of the United States, and resident of Newton, county of Middlesex, State 5 of Massachusetts, have invented an Improvement in Garment-Clasps, of which the following description, in connection with the accompanying drawing, is a specification, like letters on the drawing representing like 10 parts.

This invention relates to clasps for hose or other garments adapted to be attached to an elastic strap or web, and the invention has 15 for its object the production of improved and efficient means for attaching the clasp to the webbing.

My invention is particularly adapted for use in connection with a garment clasp of the general character shown and described 20 in United States Patent No. 630034 granted to B. G. Clark, August 1, 1899 wherein two relatively movable clamping members are connected at their inner ends, the opening 25 and closing of the outer ends of such members being governed by suitable manually operated means. In that patent the elastic strap or web is attached to one member at its inner end and extended along its outer face or back and around its free end, forming 30 at the latter point a yielding surface or grip, and the back of the clasp is also covered or protected so that the metal will not contact with the flesh of the wearer or with adjacent garments. This construction is ob- 35 jectionable in that wide and heavy webbing must be carried through slots or openings in the clasp, resulting in crinkling or warping the webbing for a considerable distance from the clasp; necessitating various adjustments 40 of the latter, and producing a somewhat unsightly and undesirable bunching of the webbing at the points where it is drawn through the clasp.

In my present invention I make the covering strip of fabric separate from the webbing, and of such a width that it will properly cover the back of the member of the clasp to which it is applied, and of a predetermined thickness, irrespective of the width or thickness 45 of the elastic web or strap which is attached to the clasp. By so doing the clasps are uniformly adjusted to close on a covering fabric always of the same width and thickness, whereas heretofore the covering material 50 has varied from a light weight, five-eighths

inch webbing to an inch and three-eighths wide heavy webbing, so that the adjustment of the clasp had to be made accordingly. If the jaws or clamping portions of the clasp were adjusted to close tightly with a firm 60 grip, using the light, narrower webbing there would be a tendency to spring the jaws if the heavier webbing were used. On the other hand if the clasp was adjusted for the heavier webbing there was the grave danger 65 that there would be no holding power or grip if the lighter webbing was used. In my present invention this objectionable feature is wholly eliminated, for as the covering strip is separate from the elastic web it 70 is immaterial whether the latter be wide or narrow, thick or thin, so far as the adjustment of the clasp is concerned, the adjustment being made for a covering fabric of uniform thickness, and it is of such width 75 that it covers the back of the clasp properly without any bunching or improper fullness. This covering strip is preferably made of in-elastic fabric, thereby reducing the expense, and the inner end of such fabric is attached 80 to the web by the same fastening means as connects the web with the clasp, facilitating assembling and again reducing the cost of manufacture.

Heretofore, in applying the broad web- 85 bing to clasps of the general type herein illustrated it was necessary to pull it through slots in the back plate of the clasp in order to attain the covering feature, and this caused the webbing to crinkle or warp for 90 some distance away from the clasp, imparting a crumpled appearance instead of lying flat and smooth, but this is overcome in my present invention so that the elastic web lies 95 flat and smooth.

These and other novel features of my in- 100 vention will be fully described in the subjoined specification and particularly pointed out in the following claim.

Figure 1 is a side elevation of a clasp em- 105 bodying one form of my present invention, the clamping members or jaws being open; Fig. 2 is an underside view of the clasp, showing the wide elastic webbing and the narrow covering strip of fabric; Fig. 3 is 110 a top plan view of the clasp, closed, with the attached webbing and covered strip; Fig. 4 is a longitudinal section taken through the center of the back plate and its loop, showing the manner in which the web-

bing is attached to the loop and the narrow covering strip to the webbing; Fig. 5 is a top plan view of the back plate of the clasp with the loop integral therewith.

5 Referring to Fig. 1 the clasp is shown as comprising a back plate or clamping member *a* having opposite ears *a'*, the coöperating clamping member *b* pivotally connected at *b*² to the plate *a* at its inner end, the member *b* having at its free end a transverse holding lip *b*³, and a longitudinally curved bearing portion *b'*, all as in the Clark patent referred to.

10 The member *a* is provided at its outer end with an upturned lip *a*³, the outer opposed ends of members *a* and *b* forming clamping jaws to engage between them the garment or other object to be held, a locking lever *d* being pivotally mounted on the 15 ears *a'* and having a rearwardly bent lug *d*³ which coöperates with the concave face of the part *b'* of the clamping member *b*, as in said patent, movement of the lever *d* to the left Fig. 1, into the position shown 20 in Fig. 3 closing the jaws. At such time the spring tongue *a*^x of the member *a* is flexed and the lug *d*³ is then so positioned that the lever *d* is held in closed position, as will be understood. The plate *a* is provided with transverse slots 1 and 2 near 25 its outer and inner ends respectively, and at the inner end the plate *a* is provided with a loop.

30 In Figs. 1 to 4 the loop 3 is shown as made of wire, and of a length considerably longer than the width of the clasp, said loop being pivotally held in an eye 4 formed by turning over upon itself the inner end of the plate *a*, the loop being made of a 35 length corresponding to the width of the elastic web or strap which is to be attached to it. I now take a strip of covering fabric 40 5, preferably inelastic, and of substantially the width of the plate *a*, and insert one end 45 through the slot 1 and beneath the plate, carrying the strip around the lip *a*³ and along the back or under face of the plate *a*, and up through the slot 2, as shown, thereby holding the strip securely on the 50 plate and retaining in place the loose end passed through the slot 1, and with the use of a minimum length of the strip or covering fabric. I thereby form a cushion or soft covering for the lip *b*³ to coöperate 55 with the fabric of the stocking or other garment when the clamping members are closed, and also to cover the back of the plate *a*, but as the strip 5 is narrow it will not bunch or pucker, and forms a neat and 60 attractive part of the clasp. This covering strip will be uniform in thickness so that the adjustment for the clasp will be made correspondingly, and entirely independent of the width or thickness of the elastic web, 65 as the latter will have no action upon the

clamping action or adjustment of the clasp. The inner end of the strip 5 is carried over the eye 4 and down through the loop 3, as at 6, where it is attached to the elastic web 7, the latter being bent to form a bight 8 70 embracing the loop, and the free end 6 of the strip 5 is tucked into the bight, and held in place by stitching 9 which also closes the bight and connects the webbing with the loop. 75

Any desired width of webbing can be used, as will be manifest, and it can be heavy or light, the webbing being permanently attached to the lighter covering strip 5 strung through the back plate of the clasp. 80 This arrangement obviates the use of a double loop with independent fastenings for the webbing and the covering strip, and I find in practice that by connecting the webbing and covering strip through the single 85 loop, and stitching them together, distributes the strain better and makes the device much stronger.

It will be seen that I completely obviate the necessity of pulling a heavy, wide piece 90 of webbing through the necessarily narrow slots of the clasp, lessening labor in construction and avoiding crumpling and unequal stretching of the webbing, which cannot be avoided when the webbing has to be 95 pulled through narrower slots.

By using a light and relatively narrow fabric for the covering strip I leave a greater space between the jaws of the clasp for receiving the stocking, corset binding, or other 100 garment to which the clasp is to be attached, whereas the heavy webbing heretofore used has made a thick bunch around the jaw of the lower clamping member, lessening the 105 jaw opening and decreasing the effective space for receiving the material of the garment.

Instead of using a separate loop I may make the same integral with the plate *a* of the clasp, as shown in Fig. 5, by increasing 110 its width at its inner end, at 10, and providing an elongated and wider slot 11, thereby constituting a loop integral with the plate and back of the narrow slot 2.

The bight of the webbing is carried 115 through the loop, as before described, and the end of the covering strip, after passing up through the slot 2 is passed down through the loop opening 11 and attached to the webbing as has been described. 120

When the loop is made integral with the back plate of the clasp it must be made substantially for a given width of webbing, but when a separate loop is used, as in Figs. 1 to 4, the length of the loop can be adapted 125 to the width of the webbing, so that for any given size of back plate various widths of webbing can be readily used.

Various changes or modifications may be 130 made in details without departing from the

spirit and scope of my invention as set forth in the annexed claim.

Having fully described my invention, what I claim as new and desire to secure by 5 Letters Patent is—

A garment clasp comprising two relatively movable clamping members connected at their inner ends, manually-operated means to govern the opening and closing of their 10 outer ends, one member having a transverse opening near each end and an elongated loop connected therewith at its inner end, a wide elastic web attached to the loop, and a narrow covering strip fabric attached to the 15 back of said web adjacent the loop and passed frontward through the loop over the

front of the clamping member and down through the adjacent transverse opening thereof and thence extended along the back of said clamping member and around the 20 outer end thereof, the outer end of the strip passing through the transverse opening at the outer end of said member to the back of the latter between it and the overlying part of the strip. 25

In testimony whereof, I have signed my name to this specification, in the presence of two subscribing witnesses.

WILLIAM P. HANNAFORD.
